EMBROIDERING DEVICE.

1,348,600.

Specification of Letters Patent.

Patented Aug. 3, 1920.

Application filed August 30, 1919. Serial No. 320,888.

To all whom it may concern:

Be it known that we, MANLIO TERRAGNI and TEOBALDO BOLDIZZONI, subjects of the King of Italy, residing in New York, in 5 the county of Bronx and State of New York, have invented certain new and useful Improvements in Embroidering Devices, of which the following is a specification.

Our invention relates to an improved embroidery device, adapted to work artistic designs in thread upon pieces of cloth.

An object of our invention is to provide an embroidery device which is simple in its make up; embracing relatively few parts, 15 and which is capable of being operated easily and efficiently by hand to produce the desired results.

Other objects of our invention are to provide an embroidery device having means 20 whereby the length of the stitch and the length of the stroke of the thread-actuating element, such as the needle, can be conveniently adjusted; and so constructed that the thread-actuating element itself serves 25 to move or feed the device over the cloth from one point to another, in practice.

Further objects and advantages of our invention will appear from the following description, taken in connection with the 30 accompanying drawings, which illustrate what we regard as the best forms of our invention; and the characteristics of our invention are defined in the appended claims. This disclosure, however, is explanatory 35 only and we reserve the right to make changes in the shape, size and arrangement of parts, without departing from the scope, and spirit of our invention to the full extent indicated by the general meanings of the 40 terms and variations of phrase in which the claims are expressed.

On the drawings:

Figure 1 is a side view of our embroidery device, broken away in one place to 45 show the same more clearly.

Fig. 2 is a front view thereof;

Figs. 3 and 4 are side and back views of the holder for the thread actuating element;

50 Figs. 5 and 6 are side views presenting the device in operation; and

Fig. 7 is a detail showing a modification.

The same numerals identify the same parts throughout.

55 In the particular description of the drawings, we employ the numeral 1 to indicate

the body of the device. This body is furnished at its lower end with an open presser foot 2, united to the body by legs 3. Above the legs, the body is tubular and it may 60 be formed out of a single piece of metal, cut and bent into the required shape. In the tubular portion of the body is a reciprocating plunger 4 connected to a holder 5 for a thread-actuating element, such as a 65 needle 6. The holder 5 projects from the lower end of the body and the needle is movable upward and downward through the foot 2; while the plunger 4 projects from the upper end of the tubular portion of the 70 body 1 and carries at its outer end a sliding head 7 to which is attached both ends of a band 8. This band forms in effect a ring to encircle the finger of the operator and enable the plunger to be moved up and 75 down to work the needle 6.

In practice the user grasps the tubular portion of the body 1 between his thumb and second finger, inserting the first or index finger through the ring 8. He then 80 presses the foot 2 against the cloth and moves the plunger up and down with his index finger by means of the head 7 and ring 8 to make one stitch after another. The plunger 4 may be simply a channel- 85 shaped piece of metal and the holder 5 may be tubular, inserted into the plunger at one end and receiving the needle at the other.

The legs 3 are provided with inclined edges 9 at the back, and the holder 5 has 90 a pair of projections 10 which engage these edges when the needle makes its downward stroke. Consequently when the device is in use and the head 7 is pressed downward, the needle will be first moved in a direction 95 that is substantially perpendicular to the surface of the cloth, which is to be embroidered; but after the point of the needle pierces the cloth, the projections 10 strike the inclined edges 9, and the remainder of 100 the movement of the needle is in a direction downward and to the rear. The backward component of the movement of the needle has the effect of impelling the presser foot 2 forward and thus moving the device into 105 proper position for the next stitch.

We arrange to regulate the length of the stroke of the needle by providing notches 11 in the edges of the plunger 4 and in engagement with these notches is an adjustable stop 12. This stop has the form of a strip which slides up and down in the tubu- 110

lar portion of the body 1 with the plunger 4; and at its outer or upper end it is bent over and widened to enter the notches. When the plunger 4 is depressed far enough 5 to carry the upper widened end of this strip 12 against the upper end of the tubular portion of the body 1; it can go no farther. For a short stroke, the stop should be inserted in one of the lower notches 11, and 10 for a long stroke it should be inserted in one of the upper notches.

We also regulate the length of the stitch by means of a pair of arms 13, pivotally attached to the outside of the legs 3 and connected by a U-shaped band 14 passing around the back of the device, making these arms act as a single member. By moving these arms rearward beyond the inclined edges 9 on the back of the legs 3, a variable 15 portion of those edges can be rendered ineffective; and the projections 10 caused to engage the inclined edges 9 at a lower point in the stroke of the needle 6. The lower the point 20 at which the projections 10 engage these edges the shorter is the distance over which 25 the needle is given a slantwise backward movement, and therefore the shorter is the stitch. Before the point of the needle pierces the cloth, the projections 10 strike 30 the arms 13. After the needle goes through the cloth, the projections 10 strike the edges 9. Hence, the movement of the needle to impel the presser foot forward does not take place until the needle engages the cloth that 35 is being worked. The arms may be tightly riveted to the legs, so that they stay set by friction.

The lower part of the holder 5 is provided with a pair of lugs 15 just below the projections 10, and through these lugs is passed 40 a pin mounting a cam 16. This cam locks the needle in the holder and enables the needle to be removed merely by turning the cam downward by means of the handle 17.

45 The head 7 carries a pin 18 which moves in slots 19 in the sides of the upper part of the plunger 4. This pin and slot engagement of the head 7 with the plunger 4 enables the head to slide to some extent in the 50 plunger; and the plunger may be provided at the top with a front portion 20 so that it encircles the head on all sides. The plunger 4 is provided with an opening 21 in the portion 20 and with a similar opening 21 in the 55 back, and the head 7 may have a passage 22 to move into and out of registry with the holes 21. The thread from a ball or spool is passed through the holes 21 and passage 22; down to a thread-guide 23 in the lower end 60 of the holder 5; and then through the eye of the needle 6. When the plunger is forced downward the holes 21 register with the 65 passage 22 and the needle can draw the thread freely; but when the upstroke is given to the needle 6, the head 7 is pulled to draw

the passage 22 out of registry with the holes 21. Thus the thread is held fast in the holes 21.

The mode of operation of the device will now be clear. A piece of cloth with a design marked thereon is secured in a frame; and the design is then worked over with thread by the operator taking hold of the body 1 between his thumb and second finger and moving the needle up and down with 75 his index finger through the ring 8; the length of the needle's stroke and the length of the stitch being first adjusted as explained above. On its forward or downward stroke through the cloth, the needle 80 makes a straight stitch on the face of the cloth bearing the design. On the upper return stroke, the head 7 binds the thread and a small loop is left on the side opposite to where the stitch is formed. See Figs. 5 and 85 6. The body 1 is held firmly with the foot 2 pressing tightly against the face of the cloth 24 which is to have the design, the cloth face being held so that this face is the upper face, while the face where the loops 25 are 90 made, will be the lower face. The loops are due to the slack in the thread, partly taken up by the upward movement of the needle after making each stitch 26.

In Fig. 7, I show a modification wherein 95 the arms 13 on the legs 3 are dispensed with. Instead of these arms, a threaded shank 13^a is fixed to the holder 5 near the projections 10, this shank extending rearward, and receiving a member or nut 27 to be screwed 100 against the plunger 4. Normally, the holder 5 is set so that on the downstroke the projections 10 strike the edges at a relatively high point, but by turning the nut forward, they can be caused to engage by the edges 9 105 at lower points, making the stitches shorter. The nut thus makes variable portions of the edges 9, ineffective, like the arms 13.

As shown in Figs. 1, 5 and 6, the arms 13 are in such position as to screen the full length of the edges 9, but obviously they will be pushed forward as far as is desired when the device is in use.

The plunger 5 may be long enough to project at both ends of the body 1 when the 115 needle is at the end of its working stroke, and the holder 5 is disposed in the plunger so that the projections 10 are near the lower end thereof. A spring 28, provided by bending down the upper end of the holder 120 keeps the holder in tight frictional engagement with the back of the plunger and the stop 12 in front, pressing the stop against the inside of the body. The holder may also have projections 29, near the spring 28 to 125 enter notches 30 in the plunger 4, so that the plunger, as it moves, will cause the holder to move with it. Thus no fastening devices for the holder and plunger are required.

Having described our invention what we believe to be new and desire to secure and protect by Letters Patent of the United States is:—

- 5 1. An embroidering device comprising a tubular body, a pair of legs, a presser foot connected to the body by said legs, a plunger movable in said body, a holder secured to one end of the plunger, a thread-actuating element affixed to the holder, said legs having inclined rear edges to be engaged by the holder and effect a feeding movement of the device to enable said element to make a stitch, a member to make variable portions 15 of said edges ineffective to regulate the length of stitch made by said element, and a slideable head at the opposite end of the plunger, said head having a passage and the plunger having openings to register with the passage on the forward stroke of said element to permit thread to be drawn therethrough, said passage and said openings being out of registry on the return stroke of the element to bind the thread against movement.
- 20 2. In an embroidering device, a body having legs with inclined edges, a holder, a thread-actuating element, said holder having lateral projections to engage said edges to effect a feeding movement of the device, a locking cam to secure the thread-actuating element thereto, and a thread guide thereon.
- 25 3. In an embroidering device, a body having legs with inclined edges, a holder, a thread-actuating element, said holder having an elastic bent-over end, lateral projections to engage said edges to effect a feeding movement of the device, a locking cam to secure the thread-actuating element thereto, and a thread guide thereon.
- 30 4. An embroidering device having a plunger, a holder for a thread-actuating element secured at one end of the plunger, said

plunger having holes therein at the opposite end, a head slidably mounted in the opposite end of the plunger and having a 45 passage to register with said holes and permit thread to be drawn therethrough by said element on the forward stroke of said element, said holes and passage being out of registry on the return stroke of the plunger 50 to hold the thread against movement.

5. An embroidering device comprising a tubular body, a pair of legs one at each side, an open presser foot connected to the body by said legs, a plunger movable in said 55 body, a holder secured to the plunger, a thread-actuating element affixed to holder and movable between said legs and through said foot, said legs having inclined rear edges to be engaged by the holder, and an 60 arm pivoted to each leg adjacent the inclined edge thereon, said arms being connected by a curved brace at the rear of the body and constituting a member to make variable portions of said edges ineffective 65 to regulate the length of stitch made by said element.

6. An embroidering device comprising a tubular body, a pair of legs, one at each side, an open presser foot connected to the 70 body by said legs, a plunger movable in said body, a thread-actuating element movable by the plunger between said legs through said foot, said legs having inclined rear edges to act upon the plunger to enable the 75 element to effect a feeding movement of said device, and a member to make variable portions of said edges ineffective, for the purpose set forth.

In testimony whereof, we have signed our 80 names to this specification this 28th day of August, 1919.
